UNITED STATES PATENT OFFICE.

WILLIAM S. ATWOOD, OF MONTREAL, QUEBEC, CANADA.

BRAKE-STEP.

1,154,160.

Specification of Letters Patent. Patented Sept. 21, 1915.

Application filed November 9, 1914. Serial No. 871,055.

To all whom it may concern:

Be it known that I, WILLIAM S. ATWOOD, a citizen of the Dominion of Canada, and resident of the city of Montreal, in the 5 Province of Quebec and Dominion of Canada, have invented certain new and useful Improvements in Brake-Steps, of which the following is a full, clear, and exact description.

10 This invention relates to improvements in brake steps for box or gondola cars, and the main object of the invention is to provide an inexpensive durable and safe step which may be applied with equal facility to 15 new or to existing cars.

A further object is to provide a step formed entirely of stamped sheet metal, and consisting of a minimum number of parts.

20 A still further object is to provide improved and simplified means for supporting the brake ratchet and pawl.

The invention consists essentially of a flanged plate having a plurality of holes stamped therein in such a way as to form 25 burs projecting from the upper surface of the plate and supporting brackets secured to the lower side of the plate preferably by electric welding.

30 The brake ratchet and pawl are journaled directly in the plate, and in a cover strap.

In the drawings which illustrate the invention: Figure 1 is a plan view of the brake step complete. Fig. 2 is a partial plan view of the step with a brake ratchet 35 and pawl and cover strap removed. Fig. 3 is a front elevation of the step complete. Fig. 4 is an end elevation. Fig. 5 is a section on the line 5—5, Fig. 1. Fig. 6 is a section of the plate 11 on the line 6—6, Fig. 1.

Referring more particularly to the drawings, 11 designates a sheet of metal of rectangular form stamped up to form an upwardly projecting flange 12 on one long 45 and two short sides, and stamped down to form a depending flange 13 on the remaining long side, which will be hereafter called the "outer edge." The surface of the plate is for the most part formed with a number 50 of regularly spaced apertures 14 punched from below in such a way as to form burs 55 projecting from the upper surface of the plate. These burs give a sure and safe foot hold for a trainman operating the brake.

55 The plate is supported toward each end by brackets 16 of stamped sheet metal suit-

ably flanged to impart stiffness. These brackets extend from the rear edge of the plate to the front edge, and are shrouded behind the depending flange 13. When 60 placed in position the brackets are electrically welded to the plate, as shown in Fig. 5, so that the three members become one.

Toward one end of the plate the apertures 14 are omitted and two comparatively large 65 apertures 17 and 18 formed a suitable distance apart, and also a suitable number of bolt holes 19. The aperture 17 which is slightly larger than the aperture 18, forms a bearing for the hub of the brake ratchet 20, 70 while the aperture 18 forms a bearing for the trunnion 21 of the pawl 22. A strap 23 is provided overlying the ratchet and pawl and as apertures 24 and 25 formed therein corresponding with the apertures 17 75 and 18, and designed for the same purpose. The strap is secured to the plate by bolts or rivets passing through the holes 19 so that it may be removed to replace a broken ratchet or pawl. It is obvious that the strap 80 may be electrically welded to the plate after the ratchet and pawl are in position, but this has the disadvantage that replacements of the ratchet or pawl are impossible.

The ratchet wheel 20 is made with either 85 square or round bore, as required, but preferably with square bore, for the reason that no pins or keys are required to hold it against revolution on the brake shaft. The step is made up complete with the ratchet 90 and pawl in place, and the cover strap bolted down, and all that is necessary in applying the device either to new or old cars, is to rivet or bolt the brackets to the end of the car and pass the brake shaft through the ratchet. 95 It will thus be seen that there is only one piece to be handled in shipping or attaching the device to cars so that great economy of time is effected. The step being formed entirely of stamped sheet metal is for all practical purposes unbreakable, and is in addition very much lighter than a cast iron step. The burs on the surface provide much better foothold than is possible with either cast iron or wooden steps, and the down turned 100 flange on one side provides for the escape of water and cinders, so that the step will give good foothold under all conditions of weather.

Having thus described my invention, what 110 I claim is as follows:—

1. A brake step comprising a flanged tread

plate burred on the upper surface, and flanged brackets supporting said plate, and welded thereto.

2. A brake step comprising a flanged plate 5 of stamped sheet metal, annular burs formed on the tread surface of said plate, and flanged brackets of stamped sheet metal welded to said plate.

3. A brake step comprising a perforated 10 tread plate of stamped sheet metal, having an upstanding flange on the three sides, and a depending flange on the fourth side, annular burs surrounding the perforations, a plurality of flanged brackets of stamped 15 sheet metal welded to the tread plate.

4. A brake step comprising an apertured 20 tread plate, supporting brackets therefor, an apertured strap carried by said plate, a ratchet wheel having the hub thereof journaled in the apertures of the plate and strap,

and a trunnioned pawl having the trunnions thereof journaled in the plate and strap apertures.

5. In a brake step, a perforated tread 25 plate of stamped sheet metal having an upstanding flange on three sides, and a depending flange on the fourth side, annular burs surrounding certain of said perforations, brackets of stamped sheet metal welded to said plate, an apertured strap bolted to the plate and a brake ratchet and pawl journaled between said plate and strap in the 30 apertures thereof.

In witness whereof, I have hereunto set my hand, in the presence of two witnesses.

WILLIAM S. ATWOOD.
